UNITED STATES PATENT OFFICE.

JOSEPH J. SZEPE, OF PITTSBURGH, PENNSYLVANIA.

DESIGN FOR A COIN AND FARE HOLDER.

59,791.

Specification for Design.

Patented Nov. 22, 1921.

Application filed July 12, 1921. Serial No. 484,206. Term of patent 7 years.

To all whom it may concern:

Be it known that I, JOSEPH J. SZEPE, a citizen of the United States, residing at Pittsburgh, in the county of Allegheny and State of Pennsylvania, have invented a new, original, and ornamental Design for Coin and Fare Holders, of which the following is a specification, reference being had to the accompanying drawing, forming part thereof.

The figure is a perspective view of a coin and fare holder showing my new design.

I claim:

The ornamental design for a coin and fare holder, as shown.

JOSEPH J. SZEPE.
